UNITED STATES PATENT OFFICE.

THOMAS JORDEN MAYBERRY, OF MOUNT GROVE, MISSOURI.

SICKLE-BAR.

SPECIFICATION forming part of Letters Patent No. 642,994, dated February 6, 1900.

Application filed June 22, 1899. Serial No. 721,481. (No model.)

To all whom it may concern:

Be it known that I, THOMAS JORDEN MAYBERRY, residing at Mount Grove, in the county of Wright and State of Missouri, have 5 invented certain new and useful Improvements in Sickle-Bars, of which the following is a specification.

This invention relates to improvements in cutter-bars for reapers and mowers; and it 10 primarily seeks to provide a novel construction of cutter-bar particularly relating to means for locking the knives to the bar in such a manner that they can be expeditiously removed in series or individually removed 15 and replaced without disconnecting the remaining knives from the cutter-bar.

This invention consists in certain details of construction and novel arrangement of parts, all of which will be hereinafter first described, 20 and then pointed out in the appended claims, reference being had to the accompanying drawings, in which—

Figure 1 is a perspective view of a cutter-bar embodying my invention. Fig. 2 is a 25 longitudinal section of the same on the line 1 1 of Fig. 1. Fig. 3 is a plan view of a sickle-bar section, showing the knives held tightly clamped from lateral movement. Fig. 4 is a detail section illustrating the manner of 30 removing the key-block at one end to permit a free lateral movement of all of the knives in the cutter-bar slot. Fig. 5 is a horizontal section taken on the line 5 5 of Fig. 4. Fig. 6 is a view of one of the knives detached, 35 and Fig. 7 is a detail view of the key-block.

The cutter-bar 1 in my construction has a longitudinal slot 2 extending from end to end and passing through from the top to the bottom of the bar. One end (the inner) of the 40 bar 1 has a transverse head portion 3, adapted to be connected with the operating-pitman, while its opposite end has a transverse member 5, the purpose of which will presently appear.

The knives 6 are of the conventional form 45 in plan view; but each knife has a pendent rib 6^a extending the full transverse width of the knife. This rib is of a size to snugly fit the slot 2 in the cutter-bar, and at one end 50 each rib has a groove 6^b and at the opposite end a tongue 6^c, said tongue and groove members being provided to admit the entire se-

ries of knives being firmly locked edge to edge, as clearly shown in Fig. 2. The knife adjacent the pitman-head has its tongue held 55 to engage a socket 3^a on the head portion 3, and the knife at the outer end of the bar has its groove facing the cross member 5.

In practice the length of the cutter-bar slot is somewhat longer than the combined length 60 of the knives held therein, whereby to permit the entire series of knives being moved laterally sufficient to allow the said entire series of knives being removed from the cutter at once or each knife removed or replaced independently of the others.

To provide for conveniently and effectively holding the several knives to their locked position and also for expeditiously adjusting the parts to permit their ready detachment 70 from the bar 1, I employ a key-block 8, adapted to fit the space between the edge of the outermost knife and the cross member 5, it having a tongue 8^a to engage the groove of the said outermost knife. The space between the 75 outermost knife and the member 5 and the relative size of the block 8 and its tongue 8^a are such that while the block 8 is held for a slight lateral adjustment within the space X its lateral movement is not sufficient to permit the said block being removed from the space X and engagement with the outermost 80 one of the knives without lifting the knife at an angle, as indicated in Fig. 4, such arrangement of parts being provided to prevent the 85 block 8 becoming accidentally displaced or lost.

The block 8 is held to its locked position by a set-screw 9, that engages a threaded opening 5^a in the member 5. To remove any or all of 90 the knives, the set-screw 9 is turned back sufficient to permit the outermost knife being tilted upward together with the key-block, as indicated in Fig. 4. This movement permits the ready removal of the key-block, it being 95 obvious that after the said block is removed the outermost knife can be dropped back in position and the entire series of knives moved laterally and all of them removed together from the slot 2, it being understood that the 100 knife adjacent the pitman end of the cutter will be sufficiently moved laterally for its tongue to disengage from the socket 3^a, it being also manifest that inasmuch as the knives

have a sufficient lateral play in the slot when the key 8 is removed to allow any one of the said knives being separated sufficient from its mates to permit it being freely removed and replaced. To again lock the knives in their position, the outermost one of the knives is tilted up sufficient to admit the tongue of the key being entered therein, after which the said end knife is again forced down, together with the key, in the slot and the said key moved up to a locking position by a proper adjustment of the set-screw 9.

I am aware that sickle-bars having knives held thereon capable of being removed independently of the others are not new, and I make no claim to such construction; but

What I do claim, and desire to secure by Letters Patent, is—

1. A cutter-bar having an uninterrupted slot extending its length and having a socket at one end of the slot; a series of knives having pendent portions adapted to fit the slot and provided with interlocking members; the end knife at one side having a tongue to engage the socket in the adjacent end of the cutter-bar, the end knife at the other side having a socket; the combined transverse width of the entire series of knives being less than the length of the cutter-bar slot, the entire series of knives having a lateral movement in the cutter-bar slot; a key-block for filling the

space intervening the end of the cutter-bar and the knives, and means for forcing the key-block tightly against the knives, as set forth.

2. A cutter-bar having an uninterrupted slot, the end wall at one side having a socket, an adjustable screw passing through the end wall of the other side; a series of knives having pendent portions adapted to snugly fit the slot, the combined width of the series of knives being less than that of the length of the slot, whereby said series are adapted for lateral movement in the slot, the end knife at one side having a tongue to engage the slot of the adjacent end of the cutter-bar, the end knife at the other side having an end groove, and a key-block adapted to fit in the space between the knives and the adjustable screw-holding end of the cutter-bar, said key-block having a tongue adapted to enter the groove of the adjacent knife, said tongue-and-grooved connection being of a greater width than the free lateral play of the key-block in the space intervening the screw-carrying end of the cutter-bar and the adjustable knife, all being arranged substantially as shown and for the purposes described.
